Fried. 1.

UNITED STATES PATENT OFFICE.

WILLIAM R. GORHAM, OF ALAMEDA, CALIFORNIA.

INTERNAL-COMBUSTION-ENGINE STRUCTURE.

1,291,837.

Specification of Letters Patent. Patented Jan. 21, 1919.

Application filed June 7, 1918, Serial No. 102,298. Renewed July 12, 1918. Serial No. 544,674.

To all whom it may concern:

Be it known that I, WILLIAM R. GORHAM, a citizen of the United States, residing at the city of Alameda, county of Alameda, 5 and State of California, have made a new and useful invention—to wit, an Improvement in Internal-Combustion-Engine Structures; and I do hereby declare the following to be a full, clear, concise, and exact description of the same.

This invention relates more particularly to the structure of the engine cylinders, the surrounding water jacket therefor and the valve mechanism.

15 In this specification and the annexed drawing I illustrate the invention in the form that I consider the best, but it is to be understood that I do not limit myself to this form because the same invention may 20 be embodied in other forms, and it is also to be understood that in and by the claims following the description, I desire to cover the invention in whatever form it may be embodied.

25 In the accompanying one sheet of drawings:

Figure 1 is a front elevation of the cylinder of an internal combustion motor in cross section built in accordance with this invention.

30 Fig. 2 is a fragmentary detail illustrating the sliding joint and packing therefor between the edge of the water jacket and the wall of the cylinder.

35 Fig. 3 is a fragmentary detail showing the shoulder stud for attaching the water jacket and manifolds to the cylinder.

40 Those portions of an internal combustion or other type of motor not germane to this invention have been omitted, this invention having more to do particularly with the cylinder and valve mechanism, the omitted portions being sufficiently well known to those skilled in this art to require no detailed disclosures herein.

45 In detail the construction illustrated in the drawings includes the cylinder 1 having the annular flange 2 by means of which it is conveniently bolted to the crank case of the motor not shown. The cylinder is preferably cast in one integral piece of cast steel, semi steel, or suitable alloy to give the maximum strength with the minimum weight and of a texture consistent with the purpose. This type of cylinder construc-

tion is especially designed for aeroplane motors where lightness, strength and reliability are primary considerations. To further lighten the structure, the water jacket 3 is preferably composed of an integral casting of aluminum alloy. This metal is light and sufficiently strong for the purpose of circulating a suitable cooling medium, such as water about the cylinder 3. Because of the inherent differences in the behavior, the metal of which the cylinder 1 is composed and the metal of which the jacket 3 is composed, novel means of combining these two elements have been resorted to to provide for the difference in the expansion and contraction particularly. The cylinder 1 is adapted to be turned to a true cylinder having parallel internal walls for the reception of the reciprocating piston operative therein in the usual manner. The head of the cylinder is preferably squared at right angles to the axis of the cylinder as at 4, the inlet and outlet passages 5 and 6 being cored into the cylinder head and internally counterbored to form the valve seats 7 and 8 against which the inlet and outlet valves 9 and 10 are adapted to seat. For convenience in forming these valve seats, the cylinder head could be formed separately and electrically or otherwise welded to the main cylinder body, but the construction shown in the drawings is the preferred form although requiring a rather more complicated method of operation in finishing the interior of the cylinder and the valve seats. The valve stems 11 and 12 project obliquely through the cylinder head being guided in the bushings 13 and 14 having shoulders thereon engaging abutments provided in the inlet and outlet passages 5 and 6. These bushings extend well beyond the head of the cylinder. The interior of the water-jacket casting is bored out to an exact fit with the head of the cylinder, over which it is forced by hydraulic pressure to insure a permanent and hermetic fitting together of the parts at all points of contact. The intake and exhaust passages register with the intake and manifold α and α' bolted to the water-jacket as hereinafter described. The lower edge of the water jacket is inturned to form the annular flange 15 registering with the annular embossment 16 formed on the cylinder walls. To render the joint water tight, at this point, the soft packing 17 is 110

introduced between the embossment 16 and the follower ring 18 surrounding the cylinder walls within the inturned flange 15, the follower ring 18 compressing the soft packing 17 under tension of the screws 19 secured into the annular flange 15, the whole combined and operating to form a water tight gland at this point, capable of a sufficient measure of expansion and contraction due to the soft packing 17 to accommodate any variation in dimension between the cylinder walls and the water jacket. The space between the water-jacket 3 and the cylinder 1 extends over the top of the cylinder through the cored triangular space 21, the latter being brought into direct contact with the superficial area of the whole cylinder so far as possible, particularly near the valves 9 and 10.

- 20 In addition to the pinch fit due to the squeezing together of the water jacket and the cylinder, positive means are provided for maintaining this relation. Such means in each instance performing an additional useful function. The bushings 13 and 14 guiding the valve stems are provided with running threads projecting beyond the water jacket and are provided with lock nuts 22 and 23 coöperating with the shoulders on the bushing to draw the cylinder head and the water jacket together and hold them in close fixed relation. The stud bolts 24 holding the manifolds α and α' in position, are threaded in the cylinder head and pass through holes provided in the water jacket and the flange 25 on the manifolds. The nuts 26 screwed onto the bolts 24 compress the water jacket between the flanges 25 and the head of the cylinder, preventing lateral displacement at this point on both sides of the structure. Further lateral stability is provided for by the hollow bushings 27 threaded into the walls of the cylinder and having the annular flange heads 28 bearing against shoulders on the water jacket to compress the jacket against the cylinder walls at this point. These hollow bushings 27 are internally threaded and adapted to receive the spark plug forming part of the ignition system of the motor. The ignition system is generally dual, requiring two plugs, one for the battery circuit and one for the magneto circuit. By these various connecting means recited, the cylinder head is pulled up into the water jacket at the top by the threaded bushings 13 and 14 on the lock nut as described and is similarly held in position laterally by the stud bolts holding the manifolds; and by the hollow bushings, and longitudinal expansion and contraction is provided for by the flange interposed between the annular flange 15 and the walls of the cylinder at the lower extremity of the water jacket.

Practice has demonstrated that the com-

pression between the water jacket and the cylinder at points of contact is sufficient to prevent leakage of water from the water jacket into the cylinder; however, white lead or any other suitable sealing medium may be introduced at these points to insure hermetic sealing.

The overhead system of valve operation illustrated in the drawings consists of a cam shaft 30 having the cam 31 fixed thereon. The cam shaft is journaled in suitable bearings supported by the brackets 32 screwed to the water jacket above the cylinder. The cams strike under the rollers 33 in the end of the rocker arms 34 pivoted at 35 in the bracket 32, the outer end of these rockers engage the valve stems to open and close the valves in accordance with the timing of the operation of the cams 31, synchronizing the opening and closing of the valves with the rotation of the crank shaft (not shown) to which the cam shaft 30 is geared by a suitable timing gearing.

The "valve in the head motor" with overhead operating cam mechanism is considered to be the most efficient, although subject to the criticism of noisiness. The noisiness can be disguised by a proper inclosing of the valve mechanism, together with proper lubrication. To this end the water jacket is formed with the upward extension 36 forming a basin around the valve mechanism, which is surmounted by the cover 37 with the interposed soft packing 38 to form an all tight seal at this point. The combination of the open base 36 and the cover 37 form a chamber entirely inclosing the valve operating mechanism, effectively muffling the noises thereof. The valve mechanism is lubricated by oil forced through the hollow cam shaft at high pressure, the inclosing chamber is filled by a fine oil spray escaping from the various bearings. This oil spray condenses on the operative parts of the valve mechanism insuring perfect lubrication at all points, the surplus oil draining back into the oil reservoirs from which it is pumped in continuous circulation. To prevent the accumulation of internal pressure within the chamber, it is vented through the openings 39 open to the atmosphere and trapped by the baffles 40 to prevent the escape of oil through the vents. For convenience in handling the cover 37, it is provided with recesses 41 having the overhanging portion 42 to form a finger hold in manipulating the cover. By disconnecting the brackets 32 from the cylinder unit, the whole cam mechanism can be removed without disturbing the timing at the valves.

The placement of the valve in the head of the cylinder as illustrated, the axis of the valve being oblique to the axis of the cylinder, permits larger valves, in proportion to

the bore of the cylinder, to be placed in the head thereof.

The cylinder and valve construction illustrated herewith does not limit or modify the multiplication of cylinders in the engine in accordance with the usual fourcycle type, in which the cylinders can be formed singly or *en bloc* or in sets of two or more, arranged vertically, horizontally, or obliquely, according to common practice.

Having thus described this invention, what I claim is:

1. In an internal combustion engine, a cylinder, an integral water jacket forced upon said cylinder, a hermetic joint provided between the said water jacket and said cylinder comprising an interned flange provided upon the lower edge of the water jacket an annular embossment formed upon the outer face of the cylinder and being adapted to register the said flange, a followup ring positioned below the embossment, means for moving such ring farther away or closer thereto and packing interposed between said embossment and ring.

2. In an internal combustion engine a cylinder, formed with internally screw threaded openings, having intake and exhaust passages opening laterally thereto, a water jacket formed with openings therethrough, hermetically engaging said cylinder, valve guides engaging the walls of said intake and exhaust passages and projecting through the head of said cylinder and the water jacket and having lock nuts thereon, manifolds formed with flanges provided with openings, bolts adapted to be passed therethrough and engage the openings in the water jacket and to project into the openings formed in the cylinder whereby to

compress the water jacket between said cylinder and manifold.

3. An internal combustion engine, comprising a cylinder, a water jacket enveloping said cylinder, such cylinder and water jacket, being provided with registering openings, a hollow valve guide positioned within such openings and being adapted to be engaged at its lower end by the cylinder and means exerting a pull at the upper end of said valve guide and pressure upon said water jacket whereby to retain the water jacket in position with respect to the cylinder.

4. An internal combustion engine, comprising a cylinder, a water jacket enveloping said cylinder, such water jacket and cylinder being provided with registering openings, a hollow valve guide, formed with a shoulder around its lower, and screw threads around its upper portion, and being adapted to be positioned within such openings in such a manner that the shoulder is engaged by the cylinder, whereby to prevent the removal of the valve guide in an upward direction, a nut adapted to engage said screw thread whereby, upon the tightening of the same, it exerts an upward pull upon the valve guide and downward pressure upon the water jacket, by reason of which the latter is retained in position with respect to the cylinder.

In testimony whereof, I have hereunto set my hand at San Francisco, California, this 31st day of May 1916.

WILLIAM R. GORHAM.

In presence of—

BALDWIN VALE,
A. J. HENRY.
